UNITED STATES PATENT OFFICE.

ORVIS W. VALLIER, OF WATERTOWN, NEW YORK, ASSIGNOR TO J. B. WISE INCORPORATED, OF WATERTOWN, NEW YORK, A CORPORATION OF NEW YORK.

FLOW REGULATOR FOR FAUCETS.

Application filed December 6, 1926. Serial No. 152,929.

This invention relates to sink faucets, and has particular reference to a novel construction and arrangement of the spout by which the water is discharged into a sink, or the like.

The object of the invention is to provide a sink faucet of the single valve type that supplies and mixes the water at various temperatures by means of a single control, wherein the discharge from the mixing chamber of the valve is effected by a swingable spout, which distributes the water to different parts of the tray of the sink. The primary object of the invention is to provide a novel, simple and effective means for preventing spattering or splashing of the water when it strikes the bottom of the sink, the said means consisting of a normally open-coil spring member, which is disposed in the water passage between the mixing chamber and the spout, and nominally performing the functions of a bushing; the said member receiving the mixture through its spaced convolutions and discharging the water directly into the spout; one end of the said member being disposed adjacent the valve chamber directly in the gravitational path of the water and adapted to contract and expand by the variations of the pressure and the volume of the water dispensed by the valve, for equalizing the volume discharge from the spout; the normal tension of said spring being such that when the valve is opened to a certain extent the entire (normal) volume of the water flows freely through the said member without contracting any of its coils and without causing any spattering after it leaves the spout, and when the valve is opened to a greater extent and accordingly discharges a larger volume at greater pressure, the normal tension of said member is overcome and the member contracts and correspondingly restricts the flow of water through its convolutions substantially to the normal volume dispensed by the initial or partial opening of the valve.

The various features and parts of the invention will be understood by the detailed description which follows, and by reference to the accompanying drawing, in which—

Figure 1 is a broken front elevation of a sink, to which my improvement is applied. Fig. 2 is a side elevation of the same. Fig. 3 is an enlarged front elevation and partial

central vertical section; showing the construction and arrangement of the tension member that controls the discharge of the water beyond the valve. Fig. 4 is an enlarged broken elevational view of the swing spout. Fig. 5 is a top plan view of the same. Fig. 6 is a fragmentary view of the neck of the spout, showing the contraction of the tension member for reducing the volume of water discharged through the spout at the highest pressure. Fig. 7 is an enlarged elevational view of the tension member. And Fig. 8 is a detached view of the plug, which closes the top end of the spring.

In the drawing, 2 represents an ordinary sink including the usual tray 2'. 3 represents the main body of the faucet, which in the present case includes a single mixing valve 4. The faucet is supported on the rear upright wall of the sink, by arms 5 and 5' (see Fig. 2), which respectively supply cold and hot water to the valve chamber 3'. The valve 4 is operable by a handle 4', which is shown, for example, in position for drawing hot water from the arm 5', and from which the water is discharged into a mixing chamber 4^b, via aligning ducts or ports 5^a—4^b. The valve is also provided with a cold water port 4^d (see Fig. 3), which is arranged to align with a similar port 5^b of the body 3. The valve 4 is tapered and seats in the correspondingly shaped chamber 3' of the body. Below the valve 4, the casing 3 is formed with a hollow externally threaded discharge neck 3^c, to which a swing-spout 6 is pivoted. The spout 6 is formed at one end with a globular portion 6', which has an upwardly facing opening 6^a, in which a bushing 7 is preferably permanently fitted, as by brazing or the like. The free or outer end of the bushing 7 is formed with an annular flange 7', which is arranged to seat against a downwardly facing shoulder or ledge 3^d of the neck 3^c. The bushing 7 above the flange 7' preferably closely but movably fits the bore of the neck. The spout 6 is detachably and swingably connected to the neck 3^c by means of a gland-nut 8 (see Figs. 1, 2 and 3). Within the nut 8 is disposed a packing 8', which is engaged by the end of the neck 3^c and prevents leakage of the joint. The nut 8 is allowed a limited axial movement by a sleeve or collar 8^a, which is loosely mounted on the bushing 7 below the flange 7'. The diameter of the said sleeve 8^a

preferably equals that of the said flange, and together with the flange effects a relatively long smooth bearing contact with a counterbore ^{3e} of the neck. This enables the spout to be swung in different directions without exerting any undue strain or wear on the parts of the joint. The water flowing into the mixing chamber ^{4b} gravitates towards the neck ^{3e} and the bushing ⁷, and ordinarily passes freely into the spout ⁶ to be discharged into the tray ², or other receptacle. In cities, the water is supplied at relatively high pressure—usually from 40 to 60 pounds per square inch—and discharges into a sink with a force that is relative to the said pressure, and except when the valve ⁴ is but slightly open, the water strikes the bottom of the sink with sufficient force to spatter over a considerable area, even beyond the borders of the sink. This spattering, which invariably increases with the further opening of the valve, is largely due to the increased volume of the water that is discharged through the enlarged opening of the valve, and by the time the valve is opened to its fullest extent, the spattering becomes a veritable spray. In order to obviate this spattering or splashing of the water, I provide a novel and simple flow or volume reducing medium, which comprises a normally open-coil spring member, as ⁹, which is disposed partially in the neck ^{3e} and partially in the globular portion ^{6'} of the spout, as best seen in Figs. 3, 4, 5 and 6. The spring ⁹ virtually performs the function of a bushing, and conducts the water received from the mixing chamber ^{3b}, and the void ^{3e} immediately below the valve ⁴, directly into the globular part ^{6'}. The top end of member ⁹ is preferably closed by the flanged head or top ¹⁰, of a solid bushing or plug ¹⁰, which is rigidly fitted into the said member. The head ¹⁰ presents a relatively broad flat surface against which the water strikes immediately after it leaves the chamber ^{4b}. Below the flange ¹⁰ the plug is formed with a cylindrical portion ^{10a}, which preferably tightly fits into the bore of the member ⁹. The tension of member ⁹ is preferably such that when the valve ⁴ is only slightly opened and discharges a relatively small volume of water by pressure too low to compress or contact the said member, the water flows freely through the openings ⁹ between the convolutions of the member, and reaches the spout ⁶ without any perceptible reduction in the volume. This free flow of the water is facilitated by a reduced lower portion ^{10b} of the plug, which is considerably smaller than the bore of the member ⁹. When however, the valve ⁴ is opened to a greater extent, a larger volume of water passes through the valve at correspondingly higher pressure. When this larger volume

of the water encounters the member ⁹, it tends to correspondingly compress and close up the convolutions of the spring ⁹, thereby restricting the flow of the water through the spout to substantially the same volume, as when the valve is only partially opened, as explained. The capacity of the ports of the valve, the mixing chamber ^{4b}, and the bore of the reducing member ⁹ as well as the tension of said member, all are preferably computed and arranged so as to effect the same flow, by volume, of the water, no matter in what position the valve ⁴ may be set, and this predetermined volume is preferably so regulated that the water strikes the bottom of the sink without any perceptible spattering or splashing. When the member ⁹ and related parts are properly constructed and arranged, a copious flow of water is insured, and all noise and spattering, as well as waste of the water, are obviated. Obviously, the convolutions of spring ⁹ may be normally separated throughout its length, as shown in Fig. 3, or a portion of the coils may be substantially closed, as shown in Fig. 7 without departing from my invention.

Having thus described my invention, what I claim, is—

1. In combination with a mixing valve having a housing with a discharge neck on the latter, a spout having a hollow head and having a bushing rotatably received in the neck and formed with an annular flange, means within the neck for engaging the flange to limit movement of the bushing out of the neck, and an open coil spring arranged in the bushing and having its lower end extending below the bushing and seated on the bottom of the head of the spout, the upper end of the spring extending above the bushing and beneath the mixing valve said bushing engaging the central part of the spring so as to compel the fluid to pass through the interior of the spring to reach the spout.

2. In combination with a mixing valve and its housing, a spout having a hollow head, means to swingably connect the head of the spout to the housing of the mixing valve, and an open coil spring having one end disposed in the head and seated on the bottom of the head so as to be supported thereby and having its opposite end disposed adjacent to the mixing valve said means engaging the central part of the spring so as to compel the fluid to pass through the interior of the spring to reach the spout.

3. In combination with a mixing valve having a housing with a discharge neck on the latter, a spout having a hollow head and having a bushing rotatably received in the neck and formed with an annular flange, a ledge in the neck engaging the upper face

of the flange, a sleeve surrounding the bushing and engaging the under face of the flange, a gland nut mounted on the neck and engaging the bottom end of the sleeve, and an open coil spring extending through and below the bushing and seated on its lower end on the bottom of the head of the spout, the upper end of the spring extending above the bushing and disposed adjacent to the mixing valve said bushing engaging the central part of the spring so as to compel the fluid to pass through the interior of the spring to reach the spout.

4. In combination with a mixing valve and its housing, a spout having a hollow

head, means to swingably connect the head of the spout to the housing of the mixing valve, including a bushing connected to the head and to the housing, and an open coil spring in the bushing having its lower end 20 projecting below the bushing and seated on the bottom of the head so as to be supported thereby and having its upper end projecting above the bushing and disposed adjacent to the mixing valve said bushing engaging the central part of the spring so as to compel the fluid to pass through the interior of the spring to reach the spout.

In testimony whereof I affix my signature.

ORVIS W. VALLIER.
